MACHINE FOR PLATFORM AND COVER
CEMENTINGWilbur L. MacKenzie, Beverly, Mass., assignor to
United Shoe Machinery Corporation, Flemington, N. J., a corporation of New Jersey

Application July 10, 1945, Serial No. 604,187

19 Claims. (Cl. 12—1)

1

This invention relates to machines for applying bands of coating material to the lasting margin of a shoe upper and to the adjacent margin of the shoe bottom member over which said lasting margin is to be drawn. It is herein illustrated as embodied in a machine for simultaneously applying bands of adhesive, hereinafter called "cement," to these surfaces.

In the manufacture of shoes having platform soles, which shoes are frequently of the slip-lasted type, it is common practice to provide the shoe bottom with a yieldable platform sole and to secure to the periphery of the upper a band of flexible material, known as the "platform cover," which is drawn over the bottom face of the platform and secured thereto by cement applied to each part. There are many different ways of providing the coating bands of cement. In some factories, the cement is applied to the whole bottom face of the platform sole while, in others, only a marginal band is utilized. Some factories apply the cement to the margin of the cover while it surrounds the shoe, while other factories wait until the platform sole has been applied and the cover turned to an upstanding position, considering the shoe in inverted position, around the periphery thereof. For the latter operation, cover-coating machines have been provided which tension the cover at the same time as they apply the band of cement to it. Whatever the procedure is, it will be realized that the cover material is always flexible and frequently is flimsy and wrinkled. For this reason, the application of a coating to it requires that the cover shall be tensioned or smoothed so that the coating may be applied uniformly thereto. Similar problems arise in coating, for cement lasting, the uppers of unlined shoes, and of certain moccasin types, which are to be lasted over a shoe-bottom member such as an insole and stuck thereto.

One object of the present invention is to provide a machine for smoothing and tensioning the margin of the cover and then extruding a coating on it.

In accordance with a feature of the invention, the problem of smoothing and/or tensioning the platform cover during the application of a coating thereto is solved in the illustrated machine, where an extruding nozzle is utilized for the application of the coating, by providing tensioning means which cooperates with the side face of the nozzle, adjacent to the outlet opening from which is delivered the coating for the cover. Adjacent to and as an adjunct to this tensioning means is a rapidly vibrating finger

2

which intermittently presses the cover against the nozzle at the outlet opening and alternately releases it at a high rate of speed. The tensioning device as shown is in the form of a roll supported upon a shaft inclined downwardly and forwardly with respect to the direction of movement of the work. This roll, pressing the cover against the side face of the nozzle has one component of force which tensions the cover widthwise and another component which assists in feeding the work.

Another important object of the invention is to provide a machine for simultaneously coating the margin of the cover and the margin of the platform sole. This is effectively carried out in the illustrated machine and in accordance with features of the invention by coating the cover as above and by utilizing both a rigidly mounted nozzle and a flexible nozzle for the application of the coating to the platform sole, thereby enabling the work to be tilted as needed by the varying curvature of the sole margin. Preferably and as shown, the same rigid nozzle is provided with a lateral opening for the coating of the cover and has associated with it the smoothing and tensioning elements previously mentioned. A driven roll engaging the shoe at the periphery of the platform sole is operator-controlled and moved out to a fixed position with respect to the nozzles and thus serves also as a gage to determine the position of the band upon the platform sole.

As illustrated, the machine embodies a device for coating the overlapping ends of the platform cover and, since this may readily be accomplished by means of a freshly coated finger to which the work may be presented, mechanism is provided for dipping this finger in a receptacle, raising it out of the coating material in the receptacle and moving it outwardly through a controlling device to limit the quantity of coating carried thereby.

These and other features of the invention will best be understood from a consideration of the following specification taken in connection with the accompanying drawings, in which

Fig. 1 is an angular view of the head of the machine;

Fig. 2 is an angular view of a shoe to which bands of coating material have been applied;

Fig. 3 is a side elevation of the machine with parts broken away;

Fig. 4 is a detailed view of a vibrating finger by which the cover is held against the nozzle;

Fig. 5 is a front elevation of the head of the

55

machine, with the nozzle broken away to show the interrelation of a tensioning roll and the vibrating finger;

Fig. 6 is a view on a larger scale of this tensioning roll and an associated abutment as well as the finger;

Fig. 7 is an enlarged angular view, showing the nozzles, the feed roll and associated parts;

Fig. 8 is a detailed section taken just above the tensioning roll on the line VIII—VIII in Fig. 6;

Fig. 9 is a elevation of the work-engaging parts observed from the left;

Fig. 10 is a similar view of these parts when in engagement with a piece of work, the latter being shown in transverse section through an inverted shoe;

Fig. 11 is a horizontal section through the lower end of the nozzle on the line XI—XI of Fig. 10;

Fig. 12 is a section through these same parts but taken at right angles to the axis of the tensioning roll and on the line XII—XII in Fig. 6;

Fig. 13 is an enlarged angular view of the combined nozzles, broken away to show a control valve for one of the nozzles;

Fig. 14 is a side elevation of these same nozzles on a smaller scale and broken away to show the delivery passages;

Fig. 15 is a detailed showing of one of the blocks of which the nozzle is made up, in inverted position;

Figs. 16 and 17 are angular views of the coacting faces of the cooperating plates which make up the fixed or rigid nozzle;

Fig. 18 is a side elevation with parts broken away and in section of a device for coating the overlapping ends of the cover material;

Fig. 19 is a similar view, showing the applicator thereof in its raised and its extended position; and

Fig. 20 is a plan view of this same device.

Supported upon a pedestal 10 (Fig. 3) is a hollow frame 12 having parallel sides 14 and 16 (Fig. 1). The upper portion 18 of the side 14 is made as a removable plate to facilitate assembly of the machine, and many of the operating parts are supported between this plate and the rear side plate 16 by means of transverse pivot pins. At the top of these side plates there is an overhanging portion 20 (Fig. 3) to the end of which is secured a block 22 which is provided with a forked nozzle support 24 (Fig. 7) having its inner faces cut back to receive the dovetail 26 on a nozzle-carrier block 28 the inner position of which is determined by an abutment screw 27. This block is held in the support 24 by a locking screw 29 and serves to support an articulated nozzle 30 and a rigid nozzle 32. Associated with the rigid nozzle for a purpose to be described are a vibrating finger 34 and a cover-tensioning roll 36 which also assists the feed of the work. Between the two is a plate 35 (Fig. 5) and below them is a feed roll 38 in engagement with the side of a lasted shoe 40 (Fig. 10) opposite the periphery of a platform sole 44 to which there is to be applied a marginal band of cement 46 (Fig. 2).

Inasmuch as the cover 48, after it is released by the machine, tends to draw or fall back, there is a danger that the cover will become stuck to the edge of the platform prior to the lasting operation. When this happens, it forces the operator of the lasting machine to pull it loose again so that it may be drawn taut around the edge of the platform. It is therefore a good

practice to position the band of coating material 52 on the cover so that a clean margin 54 is left between the inner edge of this band and the corner of the platform sole. For a similar reason, it is found preferable to leave a narrow, clean margin 47 outside of the band of material 46 which is applied to the margin of the bottom face of the platform sole. The cover 48 is usually stitched to the upper and turned down about the platform sole with its ends overlapping as at 58. It may be seen from Fig. 11 that the marginal band 46 on the sole is applied by means of the articulated nozzle 30 and by the end of the rigid nozzle 32, while the band 52 upon the cover 15 is applied by means of the rigid nozzle 32 against the side face of which the cover 48 is pressed intermittently by the vibrating finger 34. The feeding of the work is accomplished by the combined action of the tensioning roll 36 and the 20 shoe feeding roll 38. As in the shoe bottom coating machine shown in Letters Patent of the United States No. 2,195,416, granted April 2, 1940, upon my application, the nozzle is supplied with cement from a tank 60 (Fig. 3) associated with 25 which is a gear pump 62 connected to the nozzle by means of a flexible hose 64. The pressure, measured by a gage 66, is controlled by an adjustable by-pass valve 68.

As noted above, the application of the marginal band of cement to the platform sole is effected 30 chiefly by means of the flexible articulated nozzle 30 which comprises the carrier block 28 (Fig. 13) having vertical passages 70 and 72 connected at their upper ends to a recess 74 in a block 76 (Fig. 15). This recess communicates with a vertical passage 78 in a block 80 having an upwardly extending stem 82 in which there is embodied a 35 shut-off valve 84 (Fig. 7) and which is connected to the flexible hose 64 (Fig. 5). The yieldable 40 and articulated nozzle 30 is constructed as shown in Letters Patent of the United States No. 2,177,- 666, granted October 31, 1939, on an application of MacKenzie et al. It includes a support 86 to which there is attached a recessed tube plate 88 45 communicating with the vertical passage 72, through a passage 90 (Fig. 14). Pivoted on the support 86 are a series of fingers 92 each having in its bottom face an outlet opening supplied with cement through an individual tube 94. These fingers are held in contact with the work 50 by wire springs 96 carried by a plate 98.

The nozzle carrier block 28 is also provided with a depending portion 100 to which there is attached a rigid nozzle 32. This comprises an inner plate 102 having in its outer face a downwardly extending recess 104 (Fig. 17) communicating at its upper end with a perforation 106 which joins a horizontal passage 108 leading to the vertical passage 70. The flow from one to the 60 other passage is controlled by a needle valve 110, thus permitting control of the relative quantities delivered to the flexible nozzle 30 and to the rigid nozzle 32. Associated with and covering the recess 104 on the inner plate 102 is an outer plate 112 having near its lower end a recess 114 (Fig. 16) open at one side to provide an upright outlet slot 116 (Figs. 12 and 13). This recess has a bottom outlet 120 to apply part of the band of cement 46 to the platform. It will be appreciated that the outlet slot 116 applies the band of cement 52 to the cover, and that the position of this band with respect to the corner of the platform sole is determined by the positioning and gaging effect of the end of the rigidly mounted nozzle, which limits upward movement of the

shoe by its contact with the platform sole. On the outer face of this cover plate 112 are V-shaped grooves 118 (Fig. 10) intersecting one side of the recess 114 to prevent the work from shutting off the flow of cement when, as at corners of a square toe, it hugs the nozzle closely. A dowel 122 in the inner plate 102 assists in locating the cover plate 112 which is held by screws 124. It will be noted from Figs. 11 and 13 that the back plate 102 of the rigid nozzle has a rearward extension 126 against which the upstanding cover 48 is pressed by the tensioning roll 36.

This tensioning roll 36 has teeth 130 made by 90° axial cuts and 60° circumferential cuts and, since it is carried by a shaft 132 which, as viewed in side elevation is in a vertical plane and as viewed in Fig. 5 is inclined downwardly and forwardly with respect to the direction of movement of the work, its action will be divided into two components as it is rotated clockwise when viewed from above. One of these draws the cover upwardly upon the side face of the nozzle extension 126 and the other helps to feed the work forwardly. The insertion of a piece of work and its later withdrawal is facilitated by mounting the shaft 132 in a sleeve 134 having at its upper end an enlargement 136 which is swingable between pivot pins 138 (Fig. 5). These pins are adjustably mounted in the forked lower end 139 of a subframe 140 which is supported in the machine by attachment to a bracket 142 secured to the upper end of the nozzle block 22. The subframe provides further support of a driven shaft 144 having a pulley 146. The shaft 144 is connected to the roll shaft 132 by universal joints 148, thus permitting the tilting of the roll shaft without interfering with the drive. The swinging of this roll shaft is under the control of the operator by connections to be later described. The universal joints 148 are protected by a cover 149 (Fig. 1).

As will be noted from Fig. 6, there is a substantial space between the vibrating finger 34 and the tensioning roll 36, and it has been found that, if the finger is enlarged to nearly fill this space while still permitting relative movement, then, under certain conditions, there is a tendency for the material to be drawn between the edge of the finger and the toothed roll. Accordingly, a plate 35 has been provided to occupy this space. This plate has an upwardly extending part 141 (Fig. 8) held on the bearing sleeve 134 by means of screws 143 passing through a boss 145 at the lower end of the sleeve. Inasmuch as this plate 35 occupies a fixed relation to the tensioning roll 36, its edge is recessed, as at 147 (Fig. 11), and notched to fit the periphery of the tensioning roll and thereby to avoid any possibility that the work will be drawn between the two. The slope of the advancing faces of the teeth 130, as made by the 90° axial cuts during manufacture, facilitates a sort of stripping action by the thin edge of the plate 35.

At the same time as the cover is tensioned, the vibrating finger 34 is oscillated intermittently to press the cover firmly against the outlet 116 of the rigid nozzle and then to release it to permit the feeding of the work. The finger 34 thus serves as an abutment approximately opposite the outlet 116. This action smooths out wrinkles in the cover and assures the application of a continuous coating. The finger itself is an extension of a lever 150 which is pivoted on a stud 151 (Figs. 6 and 7) at the lower arm of a lever 152 supported (Fig. 9) by means of a bracket 154.

carried on the lower face of the nozzle block 22. Vibrations are imparted to the finger lever 150 through a rod 156 (Fig. 3) extending to a lever 158 the lower end of which is provided with a cam roll 160 received in a sinuous groove 162 in the side face of a cam 164, as in the machine of the Patent No. 2,195,416 mentioned above. The locus of the oscillations may readily be adjusted by means of a latched arm 166 attached to an eccentric bearing for the lever 158.

The feed roll 38 is journaled in a slidable block 170 (Fig. 3) joined by an extension 172 to a bell crank lever 174 mounted on the same pivot as is the eccentric bearing attached to the arm 166. This extension 172 is reciprocable with the block 170 to carry the roll 38 toward and away from the work and is slotted to receive an eccentric portion 176 of an adjustable bolt 178 extending between the side frame plate 16 and the removable plate 18. By partial rotation of the bolt, the locus of the path of movement of the block is determined so that the feed roll 38 may be brought against the work as close to the end of the vibrating finger 34 as feasible.

Power to drive the various operating parts of the machine is provided from a source of power such as a motor (not shown) connected by a belt 182 (Fig. 5) to a drive shaft 184. On the shaft there is mounted the cam 164 (Fig. 3), already described, pinions (not shown) for driving the pump 62, and a worm gear (not shown) connected to a worm 186 on a short shaft 188, which is connected by extensible universal joints 189, 191 to a shaft 194 in the block 170 which supports the feed roll 38. The connection of the shaft 194 to the feed roll 38 is through a series of miter gears including those shown at 196. A belt connection 200 (Fig. 5) to a countershaft 202 provides power for driving a belt 204 which passes over idlers 206 on brackets 208 and surrounds the pulley 146 for driving the shaft 132 of the tensioning roll 36. Damage to thick portions of the work is avoided by the slipping of an adjustable friction clutch 209 between the belt 200 and the countershaft 202. Adjustment of the friction clutch is also useful in varying the action of the tensioning roll upon different kinds of materials so that the desired tension will be imparted without tearing the material.

Since it is desired that the feed roll 38, the tensioning roll 36, and the vibrating finger 34 shall be separated from the nozzles when a piece of work is to be inserted or removed, operator-controlled devices have been provided for imparting movement to various levers before mentioned which control the position of these parts. Accordingly, a treadle (not shown) is connected to a treadle rod 210 (Fig. 3) the upper end of which has a fork 212 pivotally joined to the right-hand arm of a bell crank 214 which is supported on a pivot 216 carried by a bracket 218 (Figs. 1 and 3) depending from the side frame 16. Rotation of the bell crank 214 is limited by a stop screw 192 engaging a shoulder 250 on the bell crank. Supported on this treadle rod is a collar 218 bearing against a horizontally extending arm of the bell crank 214 the other arm of which is joined to the extension 172 of the feed roll block 170. This arm is normally held in the position shown in Fig. 3 by a spring 222 when the treadle is not depressed. When it is depressed, the extension 172, pushed to the left, carries the feed roll 38 against the side of the shoe. The extent to which the roll 38 is moved outward is determined by the setting of

the collar 218 on the treadle rod 210 and the movement of the latter is limited by the stop screw 192. As the treadle will always be brought to a fixed position determined by the screw 192, the feed roll 38 will act as a gage for the work pressed against it and locate the band 46 on the sole and fix the width of the clean margin 41. A lost motion connection 224 is also provided between the pivot pin of the treadle-rod fork 212 and a lever 226 carried by the pivot 216 and arranged, in opposition to a return spring 227, to operate the shut-off valve 84. This valve operation is accomplished by means of a vertical rod 228 connected to the rearwardly extending arm 230 attached to a rod 232 which is journaled in the bracket 211. The left end of this rod 232 has a detachable connection through universal joints, such as that at 234, to the shut-off valve.

The same bell crank 214, operated by the treadle, is utilized to shift the position of the fulcrum of the vibrating finger 34 and, to this end, its upper arm is connected to a substantially horizontal rod 240 the other end of which is joined to the upper portion of the lever 152 by an eye 242 (Fig. 7) receiving a hollow hub 244 on the lever. A stop bracket 245 carried on the block 22 coacts with the eye 242 to limit the swing of the lever 152 and hence the approach of the finger 34 to the work. When the treadle is operated to move the rod 240 endwise, yieldably because of a spring 246, it does not interfere with the continued oscillation of the finger 34 but changes the locus of its range of movement to move it close to the nozzle where the finger will contact the work.

The same movement of the treadle rod is effective to shift the tensioning roll 36 against the cover material by reason of the fact that a pin 253 on the lever 226 is arranged to underlie a lever arm 252 pivoted on the frame plate 18 and joined to another arm 254 which carries a sliding block 256 (Fig. 1) surrounding a rod 258 pivoted to an ear 260 on the sleeve 134 which carries the shaft 132 of the tensioning roll 36. This rod 258 is slidably supported in a bracket 262 which is attached to the frame and it has a stop nut 264 limiting the extent of movement of the roll 36 toward the rearward extension 126 on the nozzle. The action of the block 256 in pushing the rod against the work is yieldably exerted through a spring 266 bearing against a collar on the rod.

For the reason that covers such as that shown at 48 have one or more joints with the ends of the material overlapping as shown at 50, it becomes necessary to provide for the sticking together of these overlapping ends before the cover is fastened. There is accordingly provided on the machine a device which brings out a freshly-coated tongue or presenter 304 to which the ends of the cover may be presented and from which a sufficient coating of cement may be drawn, to stick these ends together. The lower end, resting against the periphery of the platform sole, is raised into contact with the lower side of the presenter and the upper end is pressed by the operator's finger against the upper side.

It is this device which is illustrated in Figs. 18, 19 and 20 and which is carried by a subframe 270 which is attached to the main frame by means of a bracket 272 and a brace 274 (Fig. 1). On the subframe are lugs 276 and 278 carrying a plate 280 on which are mounted guides 282 and 284 for a vertically slidable bar 286. The plate 286

280 also has a laterally extending plate 288 on which there is a pivot 290 for a treadle-operated lever 292. At the lower end of the plate 280 is supported a receptacle 294 provided with a slotted cover 296 on which there is slidably carried a narrow plate 298 apertured at 300 to receive a swinging arm 302 carrying at its lower end a curved presenter or tongue 304. Loops 299 are provided on an upper cover 301 to guide the sliding plate 298. The covers 296 and 301 are held on the receptacle 294 by thumb nuts 303. One side of the receptacle has an opening 306 through which the tongue may protrude and, inside the receptacle, there is a scraper or regulator 308 having a suitably tapered aperture for the passage of the tongue so as to remove therefrom surplus coating liquid 310. This scraper or regulator 308 has an adjustable portion 309.

The swinging arm 302 is pivotally carried at 312 on the sliding bar 286. When the lever 292 is turned by depression of a treadle (not shown) connected to a treadle rod 314, then the tongue is lifted out of the liquid in the receptacle and caused to project through the scraper and the opening 306. The connection between the lever 292 and the bar 286 is by means of a link 316 joined to a laterally extending bracket 318 secured to the bar by a screw. The limit of upward movement of the bar at which the tongue will register with the opening 306 is adjustably determined by an angle iron 320 secured to the side of the bar and arranged to contact with a stop screw 322 threaded in the upper guide 282.

The lever 292 has a shoulder 324 abutting the upper side of a lever 326 also carried by the pivot 290 and held normally in contact with the shoulder 324 by means of a coil spring 328. This spring surrounds the pivot 290 and is hooked under the actuating lever 292 at one end and rests against a pin 330 at its other end. This pin 330 is carried in a downwardly extending leg 332 of the lever 326. The lever 326 is joined to the treadle rod 314 by means of a bolt 334 and at the lower end of the leg 332 there is a stud 336 which is adapted to contact the side of the arm 302 to press it laterally after the sliding bar 286 has reached the stop screw 322. This lateral movement of the arm 302 is resisted by a leaf spring 338 fastened to the side of the arm and bearing at its upper end against a screw 340 on the arm 318. In its rest position, the parts are in the position shown in Fig. 18, with the tongue 304 immersed in the liquid. When the treadle rod is depressed, however, the lever 292 is swung to raise the bar 286 until it is stopped and thus to bring the tongue 304 opposite the outlet opening 306. Further depression of the treadle at that time turns the operating lever 326 on its pivot against the spring 328 and forces the tongue out through the opening to the position shown in dotted lines in Fig. 19 and in full lines in Fig. 20. At that time, the overlapping ends of the cover are presented one above and one below the tongue and then are pressed thereagainst by the operator's fingers and withdrawn, carrying with them a sufficient quantity of cement to stick them together. As soon as the treadle is released, the tongue 304 returns to the receptacle, and the slide 286 drops to lower it into the liquid. When the device is not in use, the outlet opening 306 is closed, as shown in Fig. 18, by a cover 342 pivoted to the bottom of the receptacle at 344 and having at its end spring clips 346 for frictional engagement with the sides of the receptacle to hold the cover in place. Evap-

oration of the liquid is also prevented by the close fit of the sliding plate 298 with the arm 302.

In the use of the machine, a piece of work such as the shoe 48 shown in Fig. 2 is held in inverted position with its lasting margin, here the cover 48, extending upwardly around the periphery of the sole or shoe-bottom member which as illustrated is the platform sole 44. This cover is raised between the rigid nozzle 32 and the vibrator finger 34, and at the same time between the tensioning roll 36 and the extension 126 of the rigid nozzle (Figs. 10, 11 and 12). The treadle is then depressed to move the feed roll 38 out against the work, to cause the tensioning roll 36 to grip the work against the nozzle and to bring the vibrating finger 34 against the part of the cover positioned opposite the outlet 116 of the rigid nozzle. In bringing the shoe into this position, the platform sole 44 will have been raised into contact with the fingers of the articulated nozzle 30 with enough force to raise these fingers slightly so that they will drag on the sole and lay the marginal band of cement 46 spaced from the edge of the sole by the clean margin 47. The position of this band with respect to the edge of the sole is determined by the rigidly positioned feed roll 38 which is not yieldable as in the patented machines but, by the construction above described, has been moved out to a fixed position in which the side of the shoe, and particularly the periphery of the platform sole, is pressed firmly against it. The cover stretched by the roll 36 and smoothed by the vibrator 34 will be given a marginal band of cement 52, leaving a clean margin 54 adjacent to the corner of the platform sole so that there will be little danger of the cement accidentally sticking the cover to the periphery of the sole before the lasting operation takes place. The position of this marginal band 52 is determined by the relation of the outlet opening 116 to the end of the nozzle 32 since, as explained above, this rigidly mounted nozzle serves to limit the upward movement of the shoe as it is presented to the machine. The operation will be continued until the whole periphery of the shoe has been treated, whereupon the treadle will be released and the joint 50 of the cover will be presented to the tongue 304 when in the position illustrated in Fig. 20. At that time, a treadle will have been depressed to bring the coated tongue out of the receptacle 294 ready for contact between the overlapping layers at the joint 50 so that cement may be wiped off upon both surfaces to stick them together.

Having thus described my invention, what I claim as new and desire to secure by Letters Patent of the United States is:

1. In a coating machine for a shoe on a last and embodying upper material with a flexible lasting margin surrounding the periphery of a sole member on the shoe and adapted to be lasted over the margin thereof, means for coating a portion of the projecting margin, means for coating a margin of the sole member, at least one of said means being a flexible nozzle, and means for supplying coating material to said coating means.

2. In a coating machine for a shoe on a last and embodying upper material with a flexible lasting margin surrounding the periphery of a sole member on the shoe and adapted to be lasted over the margin thereof, a flexible nozzle for coating the margin of said sole member, means for coating a portion of the surrounding lasting margin, and means for tensioning said margin in

a direction extending away from the bottom of a shoe.

3. In a coating machine for a shoe on a last and embodying upper material with a flexible lasting margin surrounding the periphery of a sole member on the shoe and adapted to be lasted over the margin thereof, a rigid abutment for positioning the sole member with the lasting margin extending beyond the bottom of the sole member, a flexible nozzle for applying a band of coating material to the margin of the sole member, means for coating a portion of the margin of the lasting margin, and means for tensioning the margin in a direction extending away from the bottom of the shoe.

4. In a coating machine for a shoe on a last and embodying upper material with a flexible lasting margin surrounding the periphery of the sole member on the shoe and adapted to be lasted over the margin thereof, rigidly supported means for applying a marginal band of coating material to the lasting margin, and driven tensioning means opposite said rigidly supported applying means and rotatable about an axis inclined downwardly and forwardly with respect to the direction of movement of the work, said tensioning means engaging said margin to press it against said rigidly supported means thereby to tension the margin as it is coated.

5. In a coating machine for a platform shoe having a flexible platform cover surrounding the periphery of a platform sole on the shoe, a fixedly supported nozzle for applying a marginal band of coating material to the cover, and driven tensioning means mounted on a shaft inclined downwardly and forwardly with respect to the movement of the work past the nozzle and engaging the cover to press it against said nozzle, thereby to tension it as it is coated.

6. In a machine for coating platform covers, a nozzle having a face containing an outlet opening, and a driven member coacting with that face to pull the cover taut before it passes the opening.

7. In a machine for coating platform covers, a nozzle having a side face containing an outlet opening, and a driven member coacting with that side face to pull the cover taut before it passes the opening, the end of said nozzle being positioned to serve as a gage to limit the movement of the shoe to which the cover is attached in the direction of the tensioning of the cover.

8. In a coating machine for a platform shoe having a cover surrounding the periphery of the shoe, a cover-coating nozzle applied to the inner periphery of the cover, said nozzle having a portion extending rearwardly with respect to the direction of movement of the shoe, and an inclined tensioning roll pressing the cover against said nozzle and drawing it taut as it approaches the outlet thereof.

9. In a coating machine for a shoe having a platform cover surrounding the periphery of a platform sole on the shoe, coating means applied to the inner periphery of the cover, cover-tensioning means cooperating with said coating means and inclined downwardly and forwardly with respect to the direction of movement of the shoe, a vibratory presser adjacent to said tensioning means and applied to the cover substantially opposite said coating means, and means interposed between the tensioning means and the vibratory means closely fitting the tensioning means to prevent the cover from being drawn into the space between the two.

10. In a coating machine, a rigidly supported

nozzle for applying a marginal band of coating material of predetermined width to the inner face of a platform cover, the end of said nozzle serving to limit the upward movement of a shoe to which the cover is attached, thereby to determine the width of a clean margin between the band of coating material and the corner of the platform, said nozzle end also being provided with an outlet opening to apply coating material to the margin of a platform sole on the shoe, a flexible nozzle for coating an adjacent band of the margin of the platform, and means coating with the side face of the first nozzle to tension the cover widthwise thereof.

11. In a coating machine for platform shoes, a depending rigidly supported nozzle having a lateral opening for applying coating material to the inner margin of a platform cover on a shoe moved past the nozzle and an end opening to apply a band of coating material to a platform sole thereon, a gage roll coating with the periphery of the shoe to locate the band on the sole, a roll pressing the cover against the side face of the nozzle, the axis of said roll being inclined downwardly and forwardly, and means for driving the latter roll to tension the cover and to assist in feeding the work.

12. In a machine for coating platforms and covers of shoes, adjacent nozzles for coating the cover and the platform, respectively, the cover-coating nozzle being fixed in position in the machine and having an outlet opening in one face, means for intermittently pressing the cover against the face of the nozzle, and means to aid in feeding the work past the nozzle comprising a driven roll positioned on an oblique axis to draw the cover away from the shoe along the face of the nozzle as it feeds it forward.

13. In a machine for coating platforms and covers of shoes, adjacent nozzles for coating the cover and the platform, respectively, the platform-coating nozzle having a yieldably mounted portion arranged to be lifted by the work as the latter is presented to it, the cover-coating nozzle being fixed in position in the machine and having an outlet opening in one face, means for intermittently pressing the cover against the face of the cover coating nozzle, and means to aid in feeding the work past the nozzle comprising a driven roll positioned on an oblique axis to draw the cover away from the shoe along the face of the nozzle as it feeds it forward.

14. In a machine for coating platform covers attached to shoes, a nozzle having a slit in its lateral face to coat a marginal portion of that cover, rapidly vibrating means to hold the cover against the side of the nozzle, and means cooperating with the side of the nozzle to pull the cover widthwise and feed the work forwardly.

15. In a machine for coating platform covers attached to shoes, a nozzle having a slit in its lateral face to coat a marginal portion of that cover, rapidly vibrating means to hold the cover against

the side of the nozzle, means cooperating with the side of the nozzle to pull the cover widthwise and feed the work forwardly, and means for separating the pulling means and the nozzle to permit the insertion of work.

16. In a machine for cementing platform covers, a depending nozzle having a lateral outlet opening, a depending finger supported for vibration and for bodily movement toward and away from the side of the nozzle, means for vibrating said finger toward the side face of the nozzle to press the work intermittently against the outlet opening, a valve controlling the flow of cement to the nozzle, a tensioning roll for smoothing the cover upwardly also mounted for bodily movement, and operator-controlled means for bringing said tensioning roll and said vibrating finger into operative relation with the side of the nozzle and for opening the valve leading to the nozzle.

17. In a coating machine for a platform shoe having a flexible platform cover surrounding the periphery of a platform sole on the shoe, coating means for applying bands of coating material to the upstanding cover and to the margin of the platform sole, at least one of said means being a flexible extruding nozzle, and rigid means associated with the latter applying means for spacing a band of coating material on the cover from the corner where the cover meets the sole.

18. In a coating machine for a platform shoe having a flexible platform cover surrounding the periphery of a platform sole on the shoe, a flexible nozzle for coating the margin of the platform sole, and means for tensioning and coating the cover simultaneously with the coating of the sole.

19. In a coating machine for a platform shoe having a flexible platform cover surrounding the periphery of a platform sole on the shoe, an abutment against which the platform sole may be pressed to guide the work, a flexible nozzle adjacent thereto for coating the margin of the sole, and means for coating the cover and tensioning it away from the sole as the coating is applied to the sole.

WILBUR L. MACKENZIE.
